UNITED STATES PATENT OFFICE.

GEORGE H. BENJAMIN, OF NEW YORK, N. Y.

MACHINE FOR EXTRUDING METALS.

No. 896,684.

Specification of Letters Patent. Patented Aug. 18, 1908.

Application filed December 2, 1907. Serial No. 404,734.

To all whom it may concern:

Be it known that I, GEORGE HILLARD BENJAMIN, a citizen of the United States, residing at the city, county, and State of New York, have invented an Improvement in Machines for Extruding Metals, of which the following is a specification.

My invention consists in a machine for extruding metals.

10 Heretofore, the metal to be extruded in the form of a billet has been heated in a furnace situated in proximity to the extruding machine, from which furnace it was drawn by a workman, carried to, and inserted into 15 the container of the extrusion machine, after which pressure was put upon the billet to force the metal through the die to give it the required shape. This operation in practice has been found open to the following objections: First: it required the expenditure of 20 hand labor. Second: it required considerable time to draw the billet from the furnace, and carry and insert it into the extruding machine. Third: it exposed the metal to 25 the cooling and oxidizing action of the atmosphere. Fourth: it made it practically impossible to extrude billets formed of alloys, which are only extrudable at definite temperatures.

30 It is the object of my invention to overcome the objections stated, and this is accomplished by the employment of the means which I will now proceed to describe.

The accompanying drawings will serve to 35 illustrate my invention, in which—

Figure 1 is a plan view partially in section; Fig. 2 is a partial elevation and vertical section, showing the container in the receiving position, with the billet to be extruded 40 within the container; Fig. 3 is a similar view, showing the container in the extruding position, with the billet in the container in the position to be acted upon by the pusher; and Fig. 4 is a transverse section looking from the 45 left, with the container in the position shown in Fig. 2.

The general features of the extrusion machine shown in the drawings are those disclosed in U. S. Patent No. 819,261, granted 50 to W. A. Wood, May 1, 1906, and consist generally of the following parts: A container 5, a hydraulic pusher 6, and a die 7. The particular form or construction of the extrusion machine is immaterial. Different forms 55 exist and they all may be used. It is only necessary that the container should be

mounted upon trunnions 8 and means be provided, such as a crank 9, and gears 10, for changing the position of the container from the horizontal, as shown in Fig. 3, to 60 the vertical, as shown in Fig. 2; or, preferably, to provide for complete rotation of the cylinder, for the purpose which will be hereinafter described.

The billet to be extruded I prefer to heat 65 progressively, *i. e.*,—as it is carried forward from the position where it is introduced into the furnace to the position where it is introduced into the container, and to accomplish this result I provide a rotary heating apparatus. This apparatus consists of a series of furnaces 12, 13, 14, and 15, supported upon a spider 16, mounted to rotate around a tubular bearing 17. Means is provided for rotating the spider, which consists of a gear 18, worm 70 19, shaft 20, bevel gears 21, 22, and hand-wheel 23. Of course, any other suitable means may be provided for rotating the furnaces.

Each of the furnaces 12, 13, 14, and 15 consists of a tubular casing 24, lined with fire-brick, and provided with a vertically movable bottom 25. These furnaces are provided with burners 26, through which gas and air may be admitted and subsequently ignited within the furnace. Preferably a 80 non-oxidizing flame is employed. The bearing 17 is hollow and through it the gas is carried, being introduced through an opening 27, and emitted through an opening 28, into a channel 29, communicating with a pipe 30. 90 The air is introduced through a channel 31, surrounding the tubular shaft of the spider, and is emitted into a channel 32 communicating with a pipe 33. It will be observed that the pipes 30 and 33 combine, as is usual, 95 to form the burners 26.

Situated under the container 5 is a hydraulic cylinder 34, the piston of which has an external member 35, adapted to co-operate with the movable bottom 25 of the furnaces as 100 they come into position over the cylinder 34.

The furnaces 12, 13, 14, and 15 are shown as open at the top, and covering three of these furnaces is a disk screen 36, provided with openings 37. This screen has a projection 38, which co-acts with the container 5 when the container is rotated from the vertical to the horizontal position, and serves to prevent the heated billet from slipping out of the container during the act of changing 110 from one position to the other. Situated over the screen 36 are perforated covers 40

for the furnaces, and over the container 5 a non-perforated cover 41 is placed when the container is in the position shown in Fig. 2. Above the disk 36, and between it and the 5 extrusion machine, there can be placed a hood for carrying the products of combustion from the furnaces, but owing to the fact that combustion in these furnaces is entirely controllable, such a hood is not essential.

10 In the drawings I have shown four furnaces, located below the extrusion machine. I do not limit myself to the number of furnaces, or to the position of the furnaces, nor do I limit myself in any wise to the various 15 features of construction disclosed, as, manifestly, they may be considerably varied without departing from the intent of my invention.

The mode of operation which I employ is 20 as follows: The billet 50, either cold or partially heated, is inserted into a furnace, for instance the furnace 12, when such furnace is at the position marked "A," Fig. 1, and the flame turned into the furnace. After a 25 time, *i. e.*,—after the billet within the container at the time has been extruded, such furnace is rotated to the position marked "B," and subsequently, after another extrusion has taken place, to the position marked 30 "C," and again, after another extrusion, to the position marked "D." When the furnace is in the "D" position, the container 5 is moved from the horizontal to the vertical position, *i. e.*,—from the position shown in 35 Fig. 3 to the position shown in Fig. 2. The hydraulic cylinder 34 is then operated, with the effect that its member 35 moves under the movable bottom 25 of the furnace and lifts the billet in the furnace into the cavity of the 40 container 5. Immediately, the container is rotated to the position shown in Fig. 3, and the container and die adjusted relative to each other. The pusher 6 is then driven into the container and against the billet to 45 push the metal of the billet through the die 7. Immediately afterwards, the pusher is withdrawn and the next furnace, for instance the furnace 15, which has followed the movements of, for instance the furnace 12, is 50 brought under the container and the action repeated. It sometimes happens that the end of the billet which is not extruded sticks in the forward end of the container, in which case it is necessary to remove it. This is 55 accomplished by reversely rotating the container 5 so that its forward end shall lie over the empty furnace with the flame in full play in the furnace. The heat from the furnace is sufficient to melt the material in the container, so that it may be readily removed. 60 In the case of alloys, for instance certain zinc alloys, which are friable above and below their extruding temperature, I prefer to heat the billet to a temperature above that at

which it can be extruded, that is—I progressively heat the billet in the furnaces at the A, B, and C positions. I then reduce the temperature of the billet in the furnace at the D position, no heat being turned on, to an extrudable condition, after which the billet 70 is introduced into the container without exposing it to the atmosphere, and is then subjected to pressure to drive it through the die.

Having thus described my invention, I claim:

1. In a machine for extruding metals, the combination of heating means, extruding means, and means for conveying the heated billet from the heating means to the extruding means without subjecting it to the action 80 of the atmosphere.

2. In a machine for extruding metals, the combination of movable heating means, extruding means, and means for carrying the billet directly from the heating means into 85 the extruding means.

3. In a machine for extruding metals, the combination of a series of furnaces, a container, means for carrying the heated billet from a furnace directly into the container, a 90 die, and a pusher for forcing the heated billet through the die.

4. In a machine for extruding metals, the combination of a container, a series of furnaces adapted to be moved progressively under the container, means for lifting the heated billet from the furnace which at the time is under the container into the cavity of the container, together with means for effecting the required movements of the container 100 and the furnaces.

5. In a machine for extruding metals, the combination of a container, a series of furnaces adapted to be moved progressively to and from a position in the axis of the container in a vertical position, means for lifting a heated billet from the furnace which at the time is under the container into the cavity of the container, together with means for effecting the required movements of the container 110 and furnaces, and for subjecting the billet to pressure when within the container.

6. In a machine for extruding metals, the combination of a pivoted container, a horizontally acting pusher, a die, a series of furnaces mounted on a spider and adapted for horizontal rotation under said container, means for heating said furnaces, and means for pushing the heated billet from one of said furnaces into the container when the container is in the charging position.

In testimony whereof, I affix my signature, in the presence of two witnesses.

GEO. H. BENJAMIN.
